APPARATUS FOR CASTING CURVED STEREO TYPE PLATES WITH TENSION LOCKUP POCKETS THEREIN

Charles L. Ricards, South Plainfield, and John A. Isbell, Plainfield, N. J., assignors to Wood Newspaper Machinery Corporation, Plainfield, N. J., a corporation of Virginia

Original application December 27, 1945, Serial No. 637,336. Divided and this application November 17, 1948, Serial No. 60,494

1 Claim. (Cl. 22—2)

1

This invention relates to apparatus for casting stereotype plates and more particularly to a machine for casting a stereotype plate having pockets on its inner face for the reception of tension clamps.

In the use of stereotype plates with modern high speed presses, where centrifugal force must be taken into account, the use of the conventional end clamp lock-up mechanisms to secure the plate to the printing cylinder has not proved satisfactory and it has been proposed to provide specially designed plate clamping fingers which are incorporated in the printing cylinders and which securely hold the stereotype plates in position on the cylinders under circumferential tension rather than under compression. The use of this tension lock-up mechanism has presented new problems in the manufacture of stereotype plates. If the plates are manufactured as heretofore, it is necessary to form pockets on their inner surfaces by a milling operation, or in some other suitable manner, thus necessitating a separate operation or requiring the milling operation to be performed in conjunction with some subsequent finishing step as, for instance, the shaving of the plate.

In accordance with the present invention, we provide suitable apparatus consisting of the usual casting box and plate core or cylinder in which the core is provided with a number of retractable pocket forming cores equal to the number of pockets desired in the stereotype plate, together with suitable means for projecting the cores when the plate core is moved into casting position and permitting the cores to be retracted when the plate core is moved from the casting box to permit the plate to be stripped from the cylinder.

This application is a division of our copending application Serial No. 637,336, filed December 27, 1945, entitled "Apparatus for Casting Curved Stereotype Plates with Tension Lock-Up Pockets Therein."

Other objects and advantages of the invention will be apparent from the following description taken in conjunction with the accompanying drawings, in which—

Fig. 1 is a horizontal sectional view of plate casting apparatus embodying the invention;

Fig. 2 is a vertical sectional view on line 2—2 of Fig. 1; and

2

Fig. 3 is a side elevation of the apparatus shown in Figs. 1 and 2.

The invention is shown applied to a stereotype plate casting machine of the type having a casting box 138 which is substantially semi-cylindrical in horizontal section as shown in Fig. 1, and this casting box cooperates with a semi-cylindrical core 140. The core, when in closed position, is arranged to be slightly spaced from the casting box to provide a mold cavity 142 between these parts, and when the cast plate is to be removed, the core is moved laterally out of the casting box and tilted to a substantially horizontal position in a manner known in the art. The casting box is supported by side frames 144 and the core is movably supported by rollers 146 on tracks 148 carried by the side frames. The rollers 146 are journaled on studs carried by brackets 150 mounted on the core. The lower ends of these brackets are pivotally connected to links 152 and the opposite ends of the links are pivotally mounted on studs 144 carried by the frame 156 of the machine. This method of supporting the core to permit it to assume either the vertical position shown in Fig. 3 for casting or to assume a substantially horizontal position to permit ejecting of the cast plate is well-known in the art.

In Fig. 1 of the drawings we have also illustrated the conventional slidable locking bars 204 by means of which the core is securely locked to the casting box 138 when the parts are in position for casting. A matrix 206 is also illustrated and is engaged between the locking bars 204 and the packing strips 208. The matrix moves out of the casting box 138 with the cast plate and is stripped therefrom by hand. The locking bars are moved laterally by means of a hand lever 210 which is pivoted to a stud 211 carried by one of the locking bars and simultaneous movement of the other locking bars is provided by toggle links 212 and a vertical sliding bar 214. These parts are of conventional construction.

Movement of the vertical sliding bar 214 is utilized to actuate the pocket core members. The pocket core members 216 are mounted in suitable channels in the core and the inner ends of the core members are provided with racks 218. These racks engage gear segments 220 mounted on shafts 222 and 224 at the opposite sides of the

machine. The shafts are geared in synchronism by bevel gears 226 and 228. These gears are carried by a stub shaft 230 mounted in bearings formed in brackets 232 on the inner side of the core. The stub shaft 230 is rotated by movement of the vertical sliding bar 214, the shaft being provided with a crank or lever 234 which is connected to the sliding bar by extending into an opening therein, as shown in Figs. 1 and 2.

The operation of the described apparatus will be apparent from the foregoing description. When the core 140 is moved to the vertical position adjacent the casting box for a casting operation and the lever 210 is moved upwardly from the dotted line position shown in Fig. 2 of the drawings for the purpose of locking the core to the casting box, movement of sliding bar 214 oscillates the shaft 230 which through bevel gears 226 and 228 oscillates shafts 222 and 224. Gear segments 220 carried by these shafts engage racks 218 on the core members 216 to move the core members outwardly and thus insert them in the mold cavity to form pockets of the desired size and shape when the stereotype plate is cast.

After the plate has been cast and cooled, the lever 210 is moved downward to the dotted line position shown in Fig. 2 to retract the locking bars 204 and so release the core from the casting box. Movement of the bar 214 turns the shaft 230 and, through the bevel gears 226 and 228, thus turns the shafts 222 and 224. The gear segments 220 carried by these shafts move the core members 216 inward and thus retract them from the pockets in the cast plate so as to permit removal of the plate from the core.

The molten type metal is poured into the cavity formed between the casting box and the core while the pocket core members protrude from the core surface. Thereafter, the cast plate is cooled, the plate is removed from the casting box with the core and is stripped from the core, the pocket core members being retracted to permit the stripping of the plate.

We claim:

In apparatus for casting curved stereotype plates of the type including a concave substantially semi-cylindrical casting box and a convex cylindrically surfaced core adapted to form an arcuate mold cavity therebetween, a linkage supporting said core for lateral movement relative to said casting box to permit removal of a cast plate from the mold cavity, locking bars carried by the core and movable radially thereof between unlocking and locking positions to release the core from and secure it to the casting box and a bar slidably axially of said core and connected to move said locking bars, the improvement which comprises at least two elongated pocket core members respectively slidably carried by said core adjacent opposite sides of said mold cavity and movable lengthwise from retracted positions beneath the cylinder of said core to extended positions in which their ends protrude outwardly into the mold cavity, shafts extending axially of said core, gears on said shafts, racks on said pocket core members engaging said gears, a transverse stub shaft geared to said axially extending shafts and a lever on said stub shaft engaging said axially slidable bar whereby movement of said bar slides said pocket core members lengthwise between their retracted and extended positions.
